(57) **CLAIM**

The ornamental design for a brush, as shown and described.

DESCRIPTION

FIG. 1 is a perspective view of a brush showing my invention, with the bristles removed for clarity;

FIG. 2 is a front side view thereof, with the bristles removed for clarity;

FIG. 3 is a back side view thereof;

FIG. 4 is a left side view thereof, with the right side being a mirror image;

FIG. 5 is a top side view thereof, with the bristles removed for clarity; and,

FIG. 6 is a bottom side view thereof, with the bristles removed for clarity.

The broken lines of the hole and the bristles on the bottom face and front face of the brush head section are for illustrative purposes only and form no part of the claimed design. The bottom face section and the front face section of the brush head, as indicated by broken lines, are also for illustrative purposes only and form no part of the claimed design.
